UNITED STATES PATENT OFFICE

HAROLD A. HICKS, OF DETROIT, MICHIGAN, ASSIGNOR TO FORD MOTOR COMPANY, OF DEARBORN, MICHIGAN, A CORPORATION OF DELAWARE

AIRPLANE

Application filed June 25, 1930. Serial No. 463,674.

The object of my invention is to provide an airplane having an improved type of pilot's seat, which seat shall be exceptionally strong, of simple construction, relatively 5 light in weight and inexpensive to manufacture. More particularly, my improved type of pilot's seat may be very easily adjusted, a very desirable feature where a number of pilots of different stature are employed to 10 operate the plane.

A further object of my invention is to provide an adjustable pilot's seat, the various 15 positions of which will be so controlled that pilots of different heights will assume the same positions relative to the airplane controls when the seat is adjusted to their individual requirements. To accomplish this desired result the seat is arranged to move both rearwardly and upwardly to accommodate 20 date taller pilots in contrast to the conventional adjustable seat which is arranged to move only rearwardly.

Still a further object of my invention is to provide a novel means for locking the seat 25 in any one of its various positions, this means being easily released by the pilot even when he is sitting in the seat so that the adjustment thereof may be quickly and accurately accomplished.

With these and other objects in view my 30 invention consists in the arrangement, construction, and combination of the various parts of my improved device, as described in the specification, claimed in my claim, and 35 illustrated in the accompanying drawings, in which:

Figure 1 shows a side elevation of the forward portion of an airplane fuselage, parts 40 being broken away to better illustrate the position of the pilot's seat in relation to the airplane controls.

Figure 2 shows a front elevation of my improved pilot's seat.

Figure 3 shows a perspective view of the 45 seat adjustment locking device, and

Figure 4 shows a diagrammatic view illustrating two positions in which the seat may be adjusted, particular reference being had 50 to the arrangement whereby the pilot as-

sumes the same relative position to the controls in each case.

Referring to the accompanying drawings, I have used the reference numeral 10 to indicate generally the fuselage of an airplane, the forward portion of which is partitioned off to form a pilot's cockpit. The roof portion and upper part of the fuselage adjacent to this cockpit is provided with a plurality of windows 11 to allow clear vision by the pilot. A partition 12 forms the rear wall of the cockpit, which partition extends in a vertical plane across the fuselage and a horizontal floor 13 is provided in this cockpit which is spaced from the bottom of the fuselage. An aileron and elevator controlling member 14 is pivotally mounted on the floor 13 and my improved pilot seat is placed directly back of this member so as to be conveniently operable therefrom. Likewise, a pair of foot operated 70 pedals 29 are disposed directly in front of the pilot's seat to control the rudder of the plane.

My improved pilot seat consists of a flat seat portion 15 having a curved metal member 16 forming the back and side members to form what is termed a bucket type seat. Sheet aluminum is preferably used for the member 16 due to its lightness. A pair of tubular supporting members 17 extend vertically from the floor 13, to which they are secured by flanges 18, upwardly one on each side of the seat 15. These tubular supports are bent rearwardly at a point adjacent to the seat 15 so that their upper ends 21 extend in a diagonal direction rearwardly and upwardly to the partition 12 where they are secured thereto by flanges 19.

A pair of spaced brackets 20 are secured to each side of the member 16 in position so that diagonal portions 21 of the tubes 17 may extend therethrough when the seat is in its normal slightly tilted back position. These diagonal portions are of sufficient length that the seat can be moved a considerable distance along the inclined tubes to thereby simultaneously raise and move back or lower and move forward the seat for adjustment.

Each of the lower brackets 20 is provided 95 with a lever 22 pivotally secured at 23 to the

under side thereof, the outer ends thereof forming handles, while the inner ends are provided with plungers 24 arranged to extend through openings in the brackets in position to contact with the under side of the tube 21. A plurality of spaced openings 25 are provided in the under side of each tube portion 21, these openings 25 being in position so that as the brackets 20 are moved 10 along the plungers 24 will successively become aligned with each of the openings 25. Suitable leaf springs 26 co-act with the levers 24 to resiliently urge the plungers into the openings 25.

15 To adjust my improved seat, the pilot while sitting in the seat grasps each of the lever handles thereby releasing the plungers 24 from the particular openings in which they have been inserted and either pushes 20 backwards on the seat or allows it to slide forwardly according to the adjustment required after which, the desired position being obtained he releases the handles so that the plungers 24 are resiliently urged into the 25 nearest pair of openings 25.

I have provided a V shaped brace 27 which has its spaced ends welded to the respective upper portions of the vertical tube members 17. The apex of this V shaped brace is provided with a flange 28, which flange is secured to the floor 13 between the flanges 18 so that the two uprights 17 are effectively braced against lateral movement.

Referring to Figure 4, I have shown the 35 rudder control members 29 in position to be operated by movement of the pilot's feet to control the course of the plane. It will be seen from this view that a pilot of rather small stature, as illustrated by the full lines 40 30, will require the seat to be placed in the position illustrated by full lines 31. However, if a pilot of larger stature, as illustrated by dotted lines 32, is to be accommodated and he is to assume the same correct position relative to the airplane controls, the seat must be 45 moved both rearwardly and upwardly to the position shown by dotted lines 33. This feature is of primary importance in connection with the operation of airplanes for the 50 reason that the pilot must become familiar with the feel of the plane before he can safely handle it. With my improved device the pilot may readily adjust the seat to the position in which he has been accustomed to 55 operate an airplane.

It will be noted from Figure 4 that a line extending up from the rudder controls 29 through the forward edge of the seat 15 extends parallel to the locus of all the various 60 positions of the seat so that regardless of the size of the pilot the seat may be readily adjusted to meet his requirements.

Among the many advantages arising from the use of my improved device it may be well 65 to mention that I have provided a simple, in-

expensive and relatively light weight seat construction particularly adapted for airplane use. Further, I have provided a means whereby the seat may be quickly adjusted by the pilot even without removing himself 70 therefrom. Still further, the locus formed by the forward edge of the seat if extended would intersect the rudder control pedals so that the pilot may quickly adjust the seat to fit his various requirements and still retain 75 the correct position relative to the controls.

Some changes may be made in the arrangement, construction and combination of the various parts of my improved device without departing from the spirit of my invention, and it is my intention to cover by my 80 claim such changes as may reasonably be included within the scope thereof.

I claim as my invention:

In an airplane construction, a partition 85 disposed across the airplane fuselage forming a pilot's compartment, said compartment having foot operated controls therein spaced forwardly from said partition, a pair 90 of laterally spaced tubular supports extending upwardly in a vertical direction from the floor of the fuselage, the upper ends of said supports being bent rearwardly and upwardly in a diagonal direction and fastened to said partition, a bucket-type seat inserted 95 between the diagonal portions of said supports, said seat having a pair of brackets secured to each side thereof in which the supporting tubes are reciprocally mounted, said 100 brackets and the incline of the supports being so proportioned that when the seat is reciprocated on the tubes the forward edge thereof will move in a line which intersects 105 said controls, a series of openings in one of said tubes, an opening in one of said brackets associated in the last mentioned tube, and a hand operable lever pivotally mounted on 110 said last mentioned bracket having a plunger formed integrally therewith adapted to enter the opening in said bracket and any one of the openings in said tube, whereby gripping the lever will release said plunger from the 115 opening in which it is inserted so that the seat may be secured in any one of several positions along said tube and still the forward edge thereof will be in uniform angular relation to said controls.

HAROLD A. HICKS.
